UNITED STATES PATENT OFFICE.

HOWARD M. BARBER, OF STONINGTON, CONNECTICUT, ASSIGNOR TO C. B. COTTRELL & SONS COMPANY, OF NEW YORK, N. Y., A CORPORATION OF DELAWARE.

MACHINE FOR CUTTING AND FEEDING SHEETS OF DIFFERENT LENGTHS FROM A CONTINUOUS WEB.

Application filed February 12, 1921. Serial No. 444,447.

To all whom it may concern:

Be it known that I, HOWARD M. BARBER, a citizen of the United States, and resident of Stonington, in the county of New London and State of Connecticut, have invented a new and useful Improvement in Machines for Cutting and Feeding Sheets of Different Lengths from a Continuous Web, of which the following is a specification.

10 The object of my invention is to provide novel means for cutting sheets of any predetermined length from a continuous web and feeding them to the desired point, the varying of the lengths of the sheets cut and fed being accomplished without the necessity of changing the position or speed of the cutting device and with but slight changes in the machine.

20 A further object is to provide a device of the above character which may be readily adjustable to cut sheets which are varied in length in multiples of a unit of measurement, such as an inch, and in fractional parts of said unit so that the very slightest 25 changes in the length of the sheet may be provided for.

This machine may be used in connection with a printing press, a folding machine, a combination printing and folding machine, or wherever it is desired to cut and feed sheets of different lengths from a continuous web.

A practical embodiment of my invention is represented in the accompanying drawings, in which,—

Fig. 1 represents the machine in side elevation.

Fig. 2 represents the machine in longitudinal central section.

Fig. 3 represents an enlarged detail top plan view of the driving mechanism.

Fig. 4 represents a detail view of a portion of the driving mechanism.

Fig. 5 represents a detail view showing a plate substituted for one of the gears carried by the driving mechanism.

In the present instance sheet folding cylinders 1 and 2 are shown, their coacting folding devices being denoted by 3 and 4. The folding cylinder 2 is shown as provided with a sheet gripping device 5 which is arranged to coact with a sheet gripping device 6 carried by the sheet feed cylinder 7.

A horizontally arranged sheet feed end-

less carrier 8 is shown as passing over the rollers 9, 10 and 11 for feeding sheets to the movable sheet stop 12 located adjacent to the cylinder 7.

The sheet cutting device herein illustrated comprises the rotary cutter 13, the knife 14 of which is arranged to coact with the knife 15 on an adjustable stationary block 16 to sever the sheets from the continuous web.

The means for feeding the web to the sheet cutting device is herein shown as comprising the primary web feeding roll 17 and the coacting secondary web feeding rolls 18, 19. These rolls may have the usual pressure rolls 20, 21, and 22. The web, not shown herein, passes from between the rolls 17 and 20 in loop form into the pocket 23; from thence over the idler roll 24 to and around the drop roll 21 and from thence around the rolls 18 and 19 over the guide 25 to the cutting device.

An auxiliary sheet feed roll 26 is provided in position to coact with the sheet feed roll 7.

The shaft of the sheet feed roll 7 is provided with a gear 27 which drives the gear 28 on the shaft of the feed roll 26, and it also drives the gear 29 on the shaft of the folding cylinder 2. This gear 29 drives the gear 30 of the folding cylinder 1.

The shaft 31 of the rotary member 13 of the sheet cutting device is driven from the shaft of the folding cylinder 2 by a chain 32 which passes around the sprocket 33 on the shaft of the folding cylinder 2 and around the sprocket 34 fast on the shaft 31 of the rotary member 13 of the sheet cutting device. This sprocket chain is also used to drive the endless sheet carrier 8 through the sprocket 35 and gears 36, 37, 38, the gear 37 being fast to the shaft of the feed roller 9. Between the sprockets 33 and 34 the chain 32 also passes around the sprockets 38, 39, 40, 41.

A worm gear 45 and a sprocket 46 are carried by a sleeve 47 loosely mounted on the cutter member shaft 31. A sprocket chain 48 passes around this sprocket 46 and also around the sprocket 49, mounted on the adjustable stud shaft 50. Meshing gears 51, 52 are mounted respectively on the shaft of the feed roll 19 and the stud shaft 50.

A sprocket 53 and a gear 54 are carried

by a sleeve 55 loosely mounted on the cutter member shaft 31. A sprocket chain 56 leads from the sprocket 53 to a sprocket 57 on the shaft 58 of the web feed roll 18.

- 5 An arm 59 is fast on the cutter member shaft 31, which arm carries a longitudinal shaft 60 and a transverse shaft 61. The longitudinal shaft 60 is provided with a worm gear 62 which meshes with the worm gear 45, carried by the sleeve 47 loosely mounted on the cutter member shaft 31. It also carries a spiral gear 63 which meshes with a spiral gear 64 on the transverse shaft 61. This transverse shaft 61 is also provided 15 with a removable gear 65 which meshes with the gear 54, carried by the sleeve 55, loosely mounted on the shaft 31.

The web feed roll 17 is driven from the web feed roll 19 by a sprocket chain 66, 20 which passes over a sprocket 67 on the shaft of the roll 17 and around a sprocket 68 on the shaft of the roll 19.

The relation of the drive for the several parts is such that the rotary cutter member 25 13 is rotated once for every two revolutions of the folding cylinders 1 and 2.

The stud shaft 50 is adjustable in an elongated slot 69 toward and away from the shaft of the feed roll 19 and the gear 52, 30 which meshes with the gear 51 may be changed to vary the lengths of the sheets in multiples of a unit of measurement, as for instance in multiples of one inch in length, by supplying the proper gear 52 and by 35 changing the position of the stud shaft 50 so that the proper gear will mesh with the gear 51. In this condition where the lengths of the sheets are varied in multiples of one inch in length, the gear 65 is removed from 40 the transverse stud shaft 61 and the shaft is held from rotating as it revolves around the shaft 31 by substituting for the gear 65, the plate 70. When the stud shaft 61 is held from rotating, the sprocket 46 makes 45 even revolutions with the rotating cutter member, thus causing the feed roll 19 to travel a predetermined number of even inches.

Where it is desired to cut sheets that are 50 varied in fractional parts of an inch in length, the plate 70 is removed and the gear 65 is replaced, thus permitting the shaft 61 to not only revolve around the shaft 31, but also to rotate on its own axis, thus causing 55 the worm gear 45 to change its position relatively to the rotating cutter member by reason of the meshing of the worm gear 45 with the worm 62 and the meshing of the spiral gear 63 with the spiral gear 64 on the 60 stud shaft 61.

As the worm gear 45 and sprocket 46 move together, it will be seen that the sprocket 46 will not make even revolutions with the rotary cutter member but is caused 65 to drop back the required amount to pro-

duce the desired length of sheet. The amount of variation in fractional parts of an inch can be obtained by changing the relation of the gears 54, 65.

From the above description it will be seen 70 that I have provided very simple and efficient means for causing sheets varying not only in multiples of a unit of measurement, but also in fractional parts of said unit, to be cut and fed from a continuous web. This 75 ability to vary the lengths of the sheets even in fractions of a unit of measurement permits a very great saving in material where the sheets are to be cut very closely to the length desired and obviates the necessity of 80 providing a machine specially built for any one predetermined length of sheet.

While I have shown the device as applied to a folding machine, it is obvious that it may be used in connection with any desired 85 mechanism where changes of folding lengths are to be cut and fed.

It is also evident that various changes may be made in the construction, form and arrangement of the several parts without 90 departing from the spirit and scope of my invention; hence I do not wish to limit myself to the particular embodiment herein shown and described, but

What I claim is:—

1. Means for cutting and feeding sheets of different lengths from a continuous web comprising a sheet cutting device having a uniformly rotating cutting member, and mechanisms separately driven by said rotary cutting member for controlling the feed of the web to cut sheets varying in length in multiples of a unit of measurement and in fractional parts of said unit.

2. Means for cutting and feeding sheets of different lengths from a continuous web comprising a sheet cutting device having a uniformly rotating cutting member, and mechanisms including a pair of coacting web feed rolls separately driven by the rotary cutting member for controlling the feed of the web to cut sheets varying in length in multiples of a unit of measurement and in fractional parts of said unit.

3. Means for cutting and feeding sheets of different lengths from a continuous web comprising a sheet cutting device having a uniformly rotating cutting member, a pair of coacting web feed rolls having separate driving connections with the rotary cutting member for controlling the movement of the web feed rolls to cut sheets varying in length in multiples of a unit of measurement and in fractional parts of said unit.

4. Means for cutting and feeding sheets of different lengths from a continuous web comprising a sheet cutting device having a uniformly rotating cutting member, a pair of coacting web feed rolls, each having a separate driving connection with said rotary

cutting member, and mechanisms for controlling the movement of said web feed rolls to cut sheets varying in length in multiples of a unit of measurement and in fractional parts of said unit.

5. Means for cutting and feeding sheets of different lengths from a continuous web comprising a sheet cutting device having a uniformly rotating cutting member, a pair of coating web feed rolls, each having a separate driving connection with said rotary cutting member, and mechanisms for controlling the movement of said web feed rolls to cut sheets varying in length in multiples of a unit of measurement and in fractional parts of said unit, and means for rendering the mechanism which controls the change in fractional parts of said unit, inoperative at pleasure.

20 6. Means for cutting and feeding sheets of different lengths from a continuous web comprising a sheet cutting device having a rotary cutting member, a pair of coating web feed rolls, each having a driving connection with said rotary cutting member, and mechanisms for controlling the movement of said web feed rolls to cut sheets varying in length in multiples of a unit of measurement and in fractional parts of said unit, and means for rendering the mechanism which controls the change in fractional parts of said unit, inoperative at pleasure, the other mechanism including a change gear.

21

30

35 7. Means for cutting and feeding sheets varying in length in multiples of a unit of measurement and in fractional parts of said unit, from a continuous web, comprising a pair of coacting web feed rolls, a sheet cutting device having a uniformly rotating member and its shaft, sprockets loosely mounted on the cutter member shaft, one sprocket having a driving connection with one web feed roll, the other web feed roll having a driving connection with the other sprocket, and a geared connection between said sprockets arranged to rotate and to revolve around said shaft.

50 8. Means for cutting and feeding sheets varying in length in multiples of a unit of measurement and in fractional parts of said unit, from a continuous web, comprising a pair of coating web feed rolls, a sheet cutting device having a uniformly rotating member and its shaft, sprockets loosely mounted on the cutter member shaft, one sprocket having a driving connection with one web feed roll, the other web feed roll having a driving connection with the other sprocket, and a geared connection between said sprockets arranged to rotate and to revolve around said shaft, said geared connection including a pair of change gears.

9. Means for cutting and feeding sheets varying in length in multiples of a unit of

measurement and in fractional parts of said unit, from a continuous web, comprising a pair of coacting web feed rolls, a sheet cutting device having a uniformly rotating member and its shaft, sprockets loosely mounted on the cutter member shaft, one sprocket having a driving connection with one web feed roll, the other web feed roll having a driving connection with the other sprocket, a geared connection between said sprockets arranged to rotate and to revolve around said shaft, and means for locking said connecting gears against rotation.

10. Means for cutting and feeding sheets varying in length in multiples of a unit of measurement and in fractional parts of said unit, from a continuous web, comprising a pair of coacting web feed rolls, a sheet cutting device having a uniformly rotating member and its shaft, sprockets loosely mounted on the cutter member shaft, one sprocket having a driving connection with one web feed roll, the other web feed roll having a driving connection with the other sprocket, a geared connection between said sprockets arranged to rotate and to revolve around said shaft, said geared connection including a pair of change gears, and means for locking said connecting gears against rotation. 80 83 90 95

11. Means for cutting and feeding sheets varying in length in multiples of a unit of measurement and in fractional parts of said unit, from a continuous web, comprising a pair of coating web feed rolls, an adjustable stud shaft having a change gear connection with one of said web feed rolls, a sheet cutting device having a uniformly rotating member and its shaft, sprockets loosely mounted on said cutter member shaft, one sprocket having a driving connection through said stud shaft with one web feed roll, the other web feed roll having a driving connection with the other sprocket, and a geared connection between said sprockets arranged to rotate and to revolve around said cutter member shaft.

12. Means for cutting and feeding sheets varying in length in multiples of a unit of measurement and in fractional parts of said unit, from a continuous web, comprising a pair of coasting web feed rolls, an adjustable stud shaft having a change gear connection with one of said web feed rolls, a sheet cutting device having a uniformly rotating member and its shaft, sprockets loosely mounted on said cutter member shaft, one sprocket having a driving connection through said stud shaft with one web feed roll, the other web feed roll having a driving connection with the other sprocket, and a geared connection between said sprockets arranged to rotate and to revolve around said cutter member shaft, said geared connection including a pair of change gears. 115
120
125
130

13. Means for cutting and feeding sheets varying in length in multiples of a unit of measurement and in fractional parts of said unit, from a continuous web, comprising a pair of coacting web feed rolls, an adjustable stud shaft having a change gear connection with one of said web feed rolls, a sheet cutting device having a uniformly rotating member and its shaft, sprockets loosely mounted on said cutter member shaft, one sprocket having a driving connection through said stud shaft with one web feed roll, the other web feed roll having a driving connection with the other sprocket, a geared connection between said sprockets arranged to rotate and to revolve around said cutter member shaft, and means for locking the connecting gears against rotation.
14. Means for cutting and feeding sheets varying in length in multiples of a unit of measurement and in fractional parts of said

unit, from a continuous web comprising a pair of coacting web feed rolls, an adjustable stud shaft having a change gear connection with one of said web feed rolls, a sheet cutting device having a uniformly rotating member and its shaft, sprockets loosely mounted on said cutter member shaft, one sprocket having a driving connection through said stud shaft with one web feed roll, the other web feed roll having a driving connection with the other sprocket, a geared connection between said sprockets arranged to rotate and to revolve around said cutter member shaft, said geared connection including a pair of change gears, and means for locking said connecting gears against rotation.

In testimony, that I claim the foregoing as my invention, I have signed my name this tenth day of February A. D. 1921.

HOWARD M. BARBER.
